UNITED STATES PATENT OFFICE.

EDWIN M. KELLOGG, OF DELAVAN, WISCONSIN, ASSIGNOR TO THE MCCORMICK HARVESTING MACHINE COMPANY, OF CHICAGO, ILLINOIS.

SHEAF-CARRIER.

SPECIFICATION forming part of Letters Patent No. 420,274, dated January 28, 1890.

Application filed May 14, 1889. Serial No. 310,738. (No model.)

To all whom it may concern:

Be it known that I, EDWIN M. KELLOGG, a citizen of the United States, residing at Delavan, in the county of Walworth and State 5 of Wisconsin, have invented certain new and useful Improvements in Sheaf-Carriers, of which the following is a specification.

The object of this invention is to construct a slatted carrier in such manner that it may 10 be tilted directly upon an axis transverse to the line of advance of the machine or parallel with the line of reception of the sheaf, but may yield and fold in, each individual finger by itself, upon meeting any obstruction or for the purpose of passing through a 15 gate, and to this end a rocking supporting-bar is mounted upon the fore part of the harvester-frame, projecting therefrom at right angles to the line of advance of the machine, 20 and to this bar are secured a series of fingers or teeth having individual pivots thereon that permit them to fold parallel with the bar. A second bar, preferably in front of the rocking bar, lies parallel therewith, and 25 is connected with said teeth by keepers—one for each tooth or for a heel-extension thereof—and is also connected with the harvester-frame by a rod or guide which permits its 30 vertical play and stops it against endwise displacement, thus insuring a sort of parallel 35 movement to the two bars and to the teeth whenever said bars are by any means swung rearward on their pivotal connections with the frame, shutting the teeth in alongside of the rocking bar. A spring holds the rocking 40 bar in its normal position at right angles to the line of advance of the machine, and a lever-connection, with controlling devices operated by the driver, enables said bar to be held against rocking on its longitudinal axis or released that the carrier-fingers may fall and dump the load.

In the drawings, Figure 1 is a top plan view of a carrier constructed according to my invention, showing also part of the harvester-frame. Fig. 2 is a rear elevation thereof, showing grain deck or chute and elevator-frame, the latter in section; Fig. 3, an elevation of the carrier from the stubble side, explaining its operation in dumping; Figs. 4

and 5, enlarged details in top plan and stubble side elevation of the mechanism for supporting and operating the carrier; Fig. 6, a like detail in transverse section seen from the rear, and Fig. 7 a top plan view of the 55 main bracket whereby said carrier is supported.

A represents the rear platform-sill and A' the rear elevator-sill, B the front platform-sill and finger-bar, and B' the front elevator-sill, of a harvester, these sills, except the front platform-sill, being herein shown as formed of square pipes, as are also the cross-girts of the elevator-frame, but this form being selected only as an exponent of any suitable construction.

C is the main wheel, and D the outer girt; E, the grain-deck receiving from the elevator E', and having at its foot or discharge end a delivery-board E², as usual in modern grain-bindlers. Automatic binding mechanism of any appropriate type will of course be located over and beneath this grain-deck; but it is not deemed necessary to show it in the drawings.

F is a supporting-bar for the carrier-fingers rocking in a horizontal bearing or bearings f, formed in a swiveling block G, which is preferably supported upon a bracket G', secured to the outer girt or one of the outer girts of 80 the machine. Toward the front end thereof the swiveling block is connected with the bracket by a pendent pivot-pin g, which turns in a vertical sleeve g' on said bracket, so that the block may be swung about in a 85 horizontal direction to permit the rocking supporting-bar to fold in toward parallelism with the girt. At its outer or stubble end the block carries a small anti-friction wheel g², traveling upon a segment-track g³, outsetting 90 from and forming part of the supporting-bracket and arranged in a horizontal plane, thus giving two points of support to the rocking bar—the first that which is due to the connection of the pivot-pin with its sleeve, and 95 the second that afforded by the segmental track; but it will be understood that this track is mainly for additional support and greater security, and may be modified or dispensed with under suitable circumstances. 100

A spring H, which may be coiled about the pivot-pin, connects the swiveling block and ultimately the rocking supporting-bar with the harvester-frame—that is to say, with the 5 outer girt or with any other suitable part of said frame—and serves to hold said bar in its normal position projecting at right angles to the advance of the machine, where it is stayed by a stop h' at the front end of the 10 segmental track against the stress of said spring.

To the rocking bar, which will be advisably of gas-pipe, is secured a series of rearwardly-projecting carrier-fingers K, each having an 15 individual upstanding pivotal connection k with said bar, so that it may be folded in theretoward and brought practically parallel therewith. These pivotal connections are herein shown as formed by a vertical bend 20 in the body of the fingers passing directly through the bar; but it is obvious that other means may be adopted.

In front of the rocking bar is another but lighter bar L, parallel therewith and connected 25 to a heel-extension l from each finger by vertical pivot-pins l', which may be integral with such heel-extension, as shown, so as to permit such extension to fold practically into line with this bar, which may be termed the 30 "controlling-bar." At the inner end said controlling-bar is bored or slotted, as at l², so as to play vertically upon a curved rod or 35 guide l³, fixed to the supporting-bracket on the end sill of the harvester-frame between 40 the seat l⁴ on the bracket and the stop l⁵ at the top of the guide, the former marking the receiving position of the carrier and the latter the limit of the dumping movement. This 45 rod or guide permits a hinge movement to the controlling-bar that it may be swung in alongside of the girt whenever the carrier meets an obstruction, but prevents endwise movement of said bar, so that as long as the rocking bar is in its normal position the carrier-fingers must remain parallel with each 50 other at right angles to said rocking bar and parallel with the line of advance of the machine.

Now, supposing that the carrier meets a 55 stump or other obstruction of such height that it cannot pass over it, the controlling-bar, and the rocking-bar as well, will be pushed back, swinging upon their pivotal connections with the machine, until they have closed in sufficiently toward the end to enable them 60 to pass the obstruction. In this movement the action of the controlling-bar upon the heel-extensions of the carrier-fingers will cause them to hinge upon their pivotal connections with the rocking bar, and, still retaining their parallelism with each other, to close in or shut in toward said bar and each other to an extent determined by the proximity of the obstruction to the end girt. As 65 soon, however, as this obstruction is passed the force of the spring will return the rocking supporting-bar to its normal position,

carrying with it the controlling-bar and the carrier-fingers, which will spread apart from each other until once again in receiving position, when further movement will be barred by the stop at the front end of the segment-track.

As thus far described, it is evident that the carrier is free to tilt whenever a sufficient 70 load is brought upon its fingers to overcome their balance, or in case that part of the fingers to the rear of the rocking bar is of sufficient weight to overcome the aggregate 75 weight of the heel-extension and controlling-bar. In order to prevent this and bring the time of tilting or discharging under the control of the driver, a long bell-crank N is arranged in front of the elevator-frame, being supported at one end in a bearing n at the 80 forward end of the outer girt and at the other end in a bearing n', projecting from the seat-plank of the machine or from a suitable part 85 of the frame. The lever-arm n² at that end adjacent to the carrier is connected by a link N' with an arm or standard N², rising from the rocking bar vertically above its pivotal connection with the supporting-bracket; or in case this arm or standard is at a measurable 90 distance from said pivotal point, then the link will be replaced by a flexible connection, so as not to obstruct the yielding movement to the rear, as above explained. The lever-arm 95 n³ at the other or inner end of the bell-crank receives one end of a foot-bar N³, extending 100 rearwardly over the seat-plank and journaled upon a stirrup O, which swings in a bearing 105 upon said seat-plank, so that when the bar is pushed to the front by the driver's foot it will hold the carrier-fingers in their receiving 110 position, and when released will allow said fingers to drop to dispose of their load. A strap o is or may be applied to the rear end 115 of the foot-bar, so that the foot which rests therein may be used to draw the bar back to aid the tilting or dumping movement in case this should be necessary.

It will be understood that the construction of my improved carrier may be somewhat varied in details, and I do not therefore intend to limit myself to the precise arrangement described herein and shown in the drawings; but

What I do claim is—

1. The combination, substantially as hereinbefore set forth, of the horizontal rocking bar, its bearing-block connected by a pendent pivotal pin to the machine, a series of carrying-fingers having independent pivotal connections with said rocking bar, and the controlling-bar parallel to said rocking bar, and also connected with said fingers by independent pivotal connections.

2. The combination, substantially as hereinbefore set forth, of the horizontal rocking bar, its bearing-block connected to the machine by a pendent pivotal pin, a series of rearwardly-extending fingers, each having a pivotal connection with said rocking bar, the

controlling-bar in front of said rocking bar and having independent pivotal connections with heel-extensions from said fingers, and the guide for the inner end of said controlling-bar.

5 3. The combination, substantially as hereinbefore set forth, of the horizontal rocking bar, its bearing-block connected to the machine by a pendent pivotal pin, a series of carrier-fingers independently connected to said rocking bar by vertical pivots, the controlling-bar, also independently connected to said fingers by vertical pivots, the guide for said controlling-bar, the standard for the rocking bar, 10 the link from said standard, and the lever system whereby the driver may rock said bar and hold it in position.

15 4. The combination, substantially as hereinbefore set forth, of the horizontal rocking bar, its bearing-block connected to the machine by a pendent pivotal connection, the spring whereby said rocking bar is normally retained in position at right angles to the advance of the machine, a series of carrier-fingers having pivotal connections with said rocking bar, the controlling-bar connected with said carrier-fingers, and the guide for 20 said controlling-bar.

25 5. The combination, substantially as hereinbefore set forth, of the supporting-bracket, its vertical sleeve and segmental track, a stop

at the forward end of said track, a swiveling bearing-block having a pendent pivotal pin taking into said sleeve and at its outer end resting upon said track, a spring whereby said swiveling block is normally retained at the forward end of said track, the rocking supporting-bar mounted in said block, a series of carrier-fingers pivoted to said supporting-bar, the controlling-bar parallel with said supporting-bar and pivotally connected to said carrier-fingers, a guide for said controlling-bar, and link-and-lever connections whereby said supporting-bar may be rocked.

35 6. The combination, substantially as hereinbefore set forth, of the supporting-bracket, its vertical sleeve and segmental track, a swiveling bearing-block having a pendent pivotal pin taking into said sleeve and at its outer end resting upon said track, the rocking supporting-bar mounted in said block, a series of carrier-fingers pivoted to said supporting-bar, the controlling-bar parallel with said supporting-bar and pivotally connected to said carrier-fingers, a guide for said controlling-bar, 40 and link-and-lever connections whereby said supporting-bar may be rocked.
